HOIST CONTROL UNIT

Filed Jan. 17, 1924

Henry H. Logan
BY Munn & Co. ATTORNEYS

UNITED STATES PATENT OFFICE.

HENRY H. LOGAN, OF CHICAGO, ILLINOIS.

HOIST-CONTROL UNIT.

Application filed January 17, 1924. Serial No. 686,850.

To all whom it may concern:

Be it known that I, HENRY H. LOGAN, a subject of the King of Great Britain, and a resident of Chicago, in the county of Cook and State of Illinois, have invented a new and useful Improvement in Hoist-Control Units, of which the following is a full, clear, and exact description.

My invention relates to improvements in hoist control unit, and it consists in the combinations, constructions, and arrangements herein described and claimed.

An object of my invention is to provide a hoist control unit for the purpose of preventing the over-winding and over-speeding of the hoisting mechanism employed for operating the skip or cage in a mine shaft.

A further object of my invention is to provide a hoist control unit of the type described for automatically shutting off the power of the hoist engine and for applying the brakes to the hoist drum, yet which is capable of independent and manual operation by the hoist engineer so that in case of failure on the part of the engineer to operate the hoist within the limits of safety for speed or limit of travel to which the control is adjusted, the control unit will automatically function without the assistance of an engineer.

A further object of my invention is to provide a device of the type described, that is compact in form, and that is supported upon a single base, thereby greatly facilitating the installation of the unit.

Other objects and advantages will appear in the following specification, and the novel features of the invention will be particularly pointed out in the appended claims.

My invention is illustrated in the accompanying drawings forming part of this application, in which—

Figure 1 is a side elevation of an embodiment of my invention, and

Figure 2 is a side elevation of a portion of the mechanism shown in Figure 1.

In carrying out my invention I make use of a brake engine consisting of a base 1 and an operating cylinder 2, mounted upon the base 1, a yoke 3 at the upper end of the cylinder 2, and a cataract cylinder 4 mounted upon the yoke 3 in axial alignment with the cylinder 2, and a piston rod 4^a, common to the cylinders 2 and 4, and arranged to project down into the base portion 1.

A valve for operating the working cylin-

der 2 is shown at 5 and is provided with a lever 6 carried by the stem of the valve. A valve for operating the cataract cylinder 4 is shown at 7 and has a lever 8 mounted on the stem thereof. A floating lever 9 is pivotally mounted intermediate its length upon the outer end of the lever 8 by means of a pin 10.

A connecting rod 13 is slidably connected at 34 with the innermost end of the lever 9 and is pivotally connected at its lowermost end with a bell crank 14. The bell crank 14 is pivotally supported at 14^b upon the yoke 3.

A control lever 14^a is disposed upon the engineer's platform and is connected by means of a rod 15 with the bell crank 14. A connecting rod 11 is pivotally connected at one end to the outermost end of the lever 8 and at its lower end to the outermost end of the lever 6. The connecting rod 11 is provided with a weight 12 which has a tendency to move the levers 6 and 8 in a clockwise direction.

It will thus be noted that movement of the lever 14^a as by manual operation by the engineer will occasion the direct actuation of the valves 5 and 7 on the working cylinder 2 and cataract cylinder 4 respectively. At this time the connecting rod 13 will bear upon the innermost end of the lever 9.

The automatic hoist control proper is shown at 16. This control is a somewhat complicated mechanism, and is of the type fully disclosed in the prior patent of W. J. Lilly, No. 1,314,675, dated September 2, 1919. This hoist control is connected directly with the hoisting drum, and driven in a predetermined ratio therewith by a shaft (not shown). The control is supported upon a bracket 17 carried by the base 1 and is so constructed as to cause the circuit breaker forming a part thereof, to actuate if the speed of the hoist drum exceeds a predetermined degree. A connecting rod 18, connected to a portion of the hoist control 16, is arranged to move longitudinally, and thereby actuate a graduated stop member 19. This operation of the rod 18 or its equivalent is fully described in the above mentioned patent and is shown at 80 in Figures 3 and 7 of the patent, and its movement is regulated by the relative position of the cage or skip and the upper and lower ends of the mine shaft.

This graduated stop 19 is fully disclosed in a patent of Mr. William J. Lilly, bearing

the Number 1,153,124, dated September 7, 1915.

A shaft 24 is rotatably mounted upon the base 1 in parallel relation to the axis of the stop member 19. A lever 20 is arranged to extend radially from the shaft 24, and carries a weight 21 at its outermost end provided with a depending portion 21^a which portion 21^a is in registration with the graduated stop 19 when the shaft 24 is permitted to rotate by a force augmented by the weight 21 in a counter-clockwise direction as viewed in Figure 1. Obviously the degree of rotation in a counter-clockwise direction of the arm 20, which is free on the shaft 24 is regulated by the particular position of the stop 19, and the graduated steps or stop portions.

Means for causing the initial movement of the shaft 24 in a counter-clockwise direction in the event of the over-speeding of the drum hoist or over-winding, is provided in a lever 22 carried by the shaft 24 having a weight 23 at the outermost end thereof. The weight 23 is normally locked in an elevated position by means of a latch 37 released through a toggle mechanism 37^a, when an electromagnet shown at 38 is de-energized, as by operation of the circuit breaker, not shown, forming a part of the controller 16, to which the magnet coils 38 are connected.

In the aforementioned Patent, No. 1,314,675, the equivalent of the magnet 38 is found at 69 (see Figure 7). The toggle 27^a is indicated at 95^a, 96, 97 and 98, and the equivalent of the latch 37 is shown at 100. The circuit breaker mentioned is illustrated in the patent in Figure 5 and operates when the circuit is closed between the wires 53^c and 51^c (see lines 60 to 75 of page 3 of the patent).

Means for cushioning the fall of the weight 23 and consequent movement of the shaft 24 is provided in a dash pot 26 supported upon a bracket 36 and having its piston pivotally connected with the lever 22.

In order that the valves 5 and 7 may operate to cause the brake engine to function at the same moment the shaft 24 is rotated, 50 by virtue of the weight 23, caused by the operation of the controller 16, I provide a connecting rod 32 pivotally connected at its lowermost end with the lever 20 and slidably connected at 85 with the innermost 55 end of the lever 6 upon the stem of the valve 5. The provision of this connecting rod 32 causes a counter-clockwise rotative movement of the stems of the valves 5 and 7 respectively, thereby actuating the working cylinder 2 and the cataract cylinder 4 simultaneously against the force exerted by the weight 12 to maintain these valves closed.

The mechanism for actuating the brake shoes associated with the brake drum of

the hoist, not shown, is provided in a stand 31 upon which a shaft 30 is rotatably mounted. An arm 27 is carried by the shaft 30 and extends radially therefrom through the base portion 1 of the brake engine. The lowermost end of the piston rod 14^a is 65 pivotally connected at 28 with the arm 27 so that when the working and cataract cylinders 2 and 4 respectively are actuated, the arm 27 is moved downwardly to the position shown in dotted lines, thereby 70 causing the shaft 30 to rotate in a counter-clockwise direction, and draw the connecting rod 29, pivotally connected upon a lug portion 30^a of the arm 27, toward the brake engine, thereby applying the brakes to the 75 hoist drum.

A brake arm weight 33 is carried by the outermost end of the arm 27.

A connection rod 39 is pivotally connected at its upper end with the outer end 85 of the floating lever 9 and at its lower end with the arm 27 adjacent to the shaft 30. The purpose of this rod 39 is to operate the floating lever 9 to bring the valves back to a neutral position as the pistons move in the cylinders 2 and 4, after a movement of the engineer's lever. In this way, the movement of the weight 33 and arm 27 follows the movement of the hand lever 14^a, and will stop at a point corresponding with the point at which the lever is stopped. The valve in the cylinder 4 then seals the piston in the position where it is when the valve closes, and prevents the weight 33 from dropping, even if the pressure ceases under 90 the lower piston.

From the foregoing description of the various parts of the device, the operation thereof may be readily understood. In general, the hoisting or lowering of the skips or cages is controlled by the operation of the lever 14^a by the engineer, thereby actuating the valves 5 and 7 of the working cylinder and cataract cylinders respectively, to cause the brake shoe operating mechanism to operate.

It should be noted that operation of the shaft 24 also causes movement of a rod 25^a which is pivotally connected to an arm 25 carried by the shaft 24, and at its opposite end to the throttle valve of the hoist engine, so that the throttle is simultaneously shut off as the brake mechanism is operated.

Let us assume that the engineer has failed to properly perform his duty and thus permitted the hoist to exceed the speed for which the control is adjusted, or permits the hoist to proceed beyond the limit of travel for which the control is set. In this event the control mechanism, as described in the prior patent of W. J. Lilly, No. 1,314,675, automatically opens the circuit of which the magnet coils 38 form a part, thereby releasing the latch 37 and permitting the

weighted levers 20 and 22 to drop. This operation causes rotation of the shaft 24 and the subsequent shut-off of the hoist engine by means of the rod 25^a. Movement 5 of the lever 20 causes the downward movement of the connecting rod 32, thereby actuating the valve lever 6, the valve 5, the connecting rod 11, and the valve 7, through the lever 8. In this manner, the brake engine 10 is operated independently of the engineer's control and the weight 33 will carry the arm 27 downwardly to cause the rod 29 to be drawn toward the brake engine, thereby setting the brakes. The degree to which 15 the brakes are applied in a unit of time is regulated by the particular position of the graduated stop 19, which in turn, as reference to the aforementioned prior patent to Lilly, No. 1,314,675 will show, will depend 20 upon the position of a cage or a skip in the shaft.

I claim:

1. A hoist control unit of the type described comprising a brake engine, a valve 25 for operating the brake engine, a brake actuating mechanism associated with said brake engine and arranged for operation thereby, a manually operated lever connected with said valve, whereby said valve may be 30 manually actuated, automatic means for operating said valve independently of said manually actuated lever, and a controller arranged for synchronism with a hoist drum, said automatic valve operating means being 35 actuated by said controller, said manually actuated lever being arranged to operate said valve entirely independent of said automatic means.

2. A hoist control unit of the type described comprising a brake engine, a valve 40 for operating the brake engine, a brake operating mechanism associated with said brake engine and arranged for operation thereby, a manually operated lever connected with said valve whereby said valve may be manually controlled, automatic means for operating said valve independently of said manually actuated lever, a con-

troller arranged for synchronism with a hoist drum, said automatic valve operating 50 means being actuated by said controller, and other means associated with said controller and actuated thereby for limiting the movement of said automatic valve operating means, said manually actuated lever being 55 arranged to operate said valve entirely independent of said automatic means.

3. In a hoist control unit of the character described, a brake engine, a valve for operating the brake engine, a manually operated lever for controlling said valve, and automatic means arranged for synchronism with a hoist drum for actuating said valve to operate said brake engine independent of the actuation of said manually operated 65 lever, said manually actuated lever being arranged to operate said valve entirely independent of said automatic means.

4. A hoist control unit of the type described comprising a brake engine having a valve for operating the brake engine, a brake actuating mechanism associated with said engine and arranged to be operated thereby, a controller arranged for synchronism with a hoist drum, a weighted lever associated 70 with the valve and arranged to operate the valve when said lever drops of its own weight, automatic means actuated by said controller for causing said weighted lever to drop and thereby actuate said valve, and 75 manually controlled means for operating said valve to actuate the brake engine independently of the actuation of said weighted lever.

5. In a hoist control unit of the character 80 described a brake engine having a valve for actuating the engine, automatic means for actuating the valve to operate the engine, and a manually operated lever for actuating said valve, said automatic means being 85 arranged to operate entirely independently of said manually controlled lever, whereby the manually operated lever remains stationary during the operation of the automatic means.

HENRY H. LOGAN.
